CLAIM

The ornamental design for a hair straightener, as shown and described.

DESCRIPTION

FIG. 1 is a perspective view of a hair straightener showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of FIG. 1 in a second state, shown with an unclaimed cap; and,

FIG. 10 is an enlarged view of the encircled portion 10 of FIG. 1.

The broken lines in the drawings are for the purpose of illustrating portions of the hair straightener that form no part of the claimed design.
